UNITED STATES PATENT OFFICE.

ALBERT M. BURRITT, OF WATERBURY, CONNECTICUT, ASSIGNOR TO THE
A. BURRITT HARDWARE COMPANY, OF SAME PLACE.

FIRE-EXTINGUISHER ALARM APPARATUS.

SPECIFICATION forming part of Letters Patent No. 270,010, dated January 2, 1883.

Application filed October 14, 1882. (No model.)

To all whom it may concern:

Be it known that I, ALBERT M. BURRITT, of Waterbury, in the county of New Haven and State of Connecticut, have invented new Improvements in Fire-Extinguisher Alarm Apparatus; and I do hereby declare the following, when taken in connection with accompanying drawings and the letters of reference marked thereon, to be a full, clear, and exact description of the same, and which said drawings constitute part of this specification, and represent, in—

Figure 1, a sectional side view; Fig. 2, a transverse section on line *xx*.

This invention relates to a device to be attached to that class of fire-extinguishing apparatus which consists in an arrangement of tubing leading from a water-supply around an apartment to be protected, with distributors at different points in the apartment, and which are automatically opened by heat generated from an accidental fire occurring in an apartment, and so that when the distributors are open the water coming through the tubing will be distributed in the apartment to extinguish the fire, the object of the device being to sound an alarm when the distributor is opened or the flow of water begins. As the pipes for the distribution of water are usually in connection with the supply for other purposes, the water-hammer produced by a sudden cutting off of the water is sufficient to operate an alarm device which is in connection with the column of water, so that a sudden movement upon the water will operate it. Hence it is necessary that some provision be made to prevent the action of the water-hammer upon the alarm device, in order to make such a device a success.

The object of my invention is a construction of valve so that the alarm device will not be affected by the water-hammer. To that end my invention consists in arranging in the water-way a hollow cylinder, substantially open at its two ends—one end to rest upon a seat in the water-way like a valve—the cylinder hung in connection with an alarm apparatus, so as to turn from its position in line with the flow of water, away from its seat, to a position substantially right angles therewith, com-

bined with a valve within said cylinder, arranged to rest at its lower end, but of little greater specific gravity than that of the water, with a small aperture through the valve, so that an equilibrium will be produced by the standing water upon the valve, and yet when the flow is opened the valve will be thrown to the opposite end of the cylinder, causing the cylinder to turn and sound the alarm, as more fully hereinafter described.

A represents the passage through which the water flows to supply the distributors, and opens into a chamber, *B*. From this chamber is an outlet, *C*, which leads to the distributing-pipes. At the entrance of the passage *A* into the chamber *B* a valve-seat, *a*, is formed.

D is a hollow cylinder, of substantially the diameter of the passage *A*, and constructed with an annular flange or projection, *b*, so that the cylinder will rest upon the valve-seat *a*, as seen in Fig. 1. At the lower end of the cylinder is an internal annular flange, *e*, and at the upper end a corresponding internal annular flange, *f*. The cylinder *D* is hung at its lower end to a yoke, *E*, which is made fast to a transverse shaft, *F*, and upon which shaft as a center the cylinder may be turned from its position over the water-passage *A* into the chamber *B*, as indicated in broken lines, Fig. 1. The shaft *F* extends outside the chamber *B*, and there carries a cam, *h*, which stands in line with one arm, *i*, of a lever hung upon a fulcrum, *l*, the other arm, *m*, provided with a latch-like notch, *n*.

To the shaft *F* a bent arm, *H*, extends into connection with a weight or spring-rod, *L*. The rod *L* is hung to one arm, *r*, of a lever, the other arm, *s*, of which engages the notch or latch *n* of the lever *m i*, and so that when the cylinder stands in its position in the water-way the lever *r s* will hold the weight-rod *L* suspended by means of the latch-lever *m i*; but as the cylinder begins to rise from its seat the cam *h* bears against the arm *i* of the latch-lever and turns the arm *m* to disengage the latch from the arm *s* of the lever or trip, and thus frees the weight-lever from its suspension, allowing it to fall, and in so falling completes the turn of the cylinder and also causes the alarm to be sounded. This alarm may be

made through a lever, P, or otherwise, in connection with the weight-rod L or other part of the mechanism.

Within the cylinder D is a valve, R, which is of somewhat less diameter than the internal diameter of the cylinder, and rests on the lower flange, e, but so as to be moved freely up and down in the cylinder. Through this valve are one or more small apertures, t, through which the water will flow to fill the chamber above and pipes beyond the valve, and establish an equilibrium upon the valve. In that condition the valve will rest upon its seat e; but if at any time the force of water-hammer comes upon the water in the passage A, it will be received by the valve R, and that valve, being of but little greater specific gravity than that of water, will be thrown up in the cylinder by the force of water-hammer and away from its seat, to which it will return as soon as the impulse given to it by the water-hammer has passed away; but if the flow of water through the passage A be opened as to supply the distributers, then the escape is greater than the apertures in the valve R. Hence that valve will, by the force of the flow, be driven to the opposite end of the cylinder, as indicated in broken lines, and against the flange f at that end of the cylinder, which will then apply the force of the flow to the cylinder and cause it to rise from its seat, and in so rising will trip the latch i m and bring the weight or spring in connection with the rod L upon the lever H, which will quickly throw the cylinder back away from the water-way and into the chamber B, as seen in broken lines, Fig. 1, thus leaving the passage clear for the flow of water. Were it not for this arrangement of the free valve and cylinder, or, in other words, if the valve were made fast to the alarm device, the water-hammer would frequently cause sufficient movement of the valve to trip the alarm apparatus and sound the alarm; but, by the employment of the hollow open cylinder in connection with the apparatus, and combining the free valve therein to receive the water-hammer and the first impulse of the flowing water, these difficulties and possible accidents are entirely overcome.

Instead of making apertures in the valve R for the passage of the water, it may be made to so loosely fit the seat as to permit the necessary flow of water around it instead of through it.

I have represented a tripping apparatus which works practically in connection with the cylinder; but it will be understood that other mechanism may be employed, to be tripped in substantially the same manner, to operate the alarm.

I claim—

1. In a fire-extinguisher alarm apparatus, the combination of a hollow cylinder, open at both ends, one end arranged upon a seat in the water-way, a free valve within said cylinder, and resting at a point near the seat of the cylinder in the water-way, with a stop in the cylinder above, so as to permit movement of the valve within and independent of the cylinder, the valve constructed for passage of water from the water-way to the chamber above it, by which an equilibrium of pressure upon the valve in the standing water will be produced, and an alarm mechanism, substantially such as described, in connection with the said cylinder, whereby the movement of the cylinder produced by the rise of the valve within the cylinder will trip the said apparatus, substantially as described.

2. In a fire-extinguisher alarm apparatus, the combination of a hollow cylinder, hung in a chamber into which the water-way opens, and seated against the inflow of water, a free valve within said cylinder arranged upon a seat near the lower end of the cylinder and so as to move within the cylinder to a stop at a point above, the said cylinder hung upon a shaft at right angles to the axis of the cylinder, and upon which shaft as a center the said cylinder will turn from its position of closing the water-way into the chamber above and away from the water-way, and mechanism, substantially such as described, in connection with said shaft, whereby the turning of the shaft by the movement of the cylinder will trip said mechanism to sound an alarm, substantially as described.

3. In a fire-extinguisher alarm apparatus, the combination of a hollow cylinder, hung in a chamber into which the water-way opens, and seated against the inflow of water, a free valve within said cylinder arranged upon the seat near the lower end of the cylinder so as to move within the cylinder to a stop at a point above, the said cylinder being hung upon a shaft at right angles to the axis of the cylinder, upon which shaft as a center the said cylinder will turn from its position of closing the water-way into the chamber, to a position above and away from the water-way, a spring or equivalent mechanism, and a trip to suspend said rod, a cam on the shaft to release the said trip, and an arm extending from said shaft to said rod, whereby when the weight or spring is tripped the power of that weight or spring will be applied to the shaft to turn the cylinder, substantially as described.

ALBERT M. BURRITT.
